UNITED STATES PATENT OFFICE.

ANTHONY V. KNOLL, OF DAVENPORT, IOWA.

RADIATOR.

1,407,428.

Specification of Letters Patent. Patented Feb. 21, 1922.

Application filed April 26, 1920. Serial No. 376,702.

To all whom it may concern:

Be it known that I, ANTHONY V. KNOLL, a citizen of the United States, and a resident of Davenport, in the county of Scott and State of Iowa, have invented a new and useful Improvement in Radiators, of which the following is a full, clear, and exact description.

My invention relates to improvements in radiators, and it consists in the combinations, constructions, and arrangements herein described and claimed.

An object of my invention is to provide a radiator having tubes in curved form whereby there is no danger of stopping of the circulation.

A further object of my invention is to provide a radiator having tubes of the form described which is braced between adjacent tubes so as to render the device strong and durable.

A further object of my invention is to provide a radiator having tubes which are of varying thicknesses along the width of the tube, the cross section of the tube presenting a fluted or corrugated contour, whereby the expansion of the tube can occur, as when the water freezes in the tubes, without injuring the latter.

30 A further object of my invention is to provide a novel form of water tube having lock seam joints, thereby preventing leaking.

A further object of my invention is to provide a tube in which the water is caused to travel a greater distance than in the ordinary straight tube, thereby insuring positive radiation.

40 A further object of my invention is to provide a radiator in which a relatively large amount of air may be admitted, thereby insuring the cooling of the water in the tube.

Other objects and advantages will appear in the following specification, and the novel features of the invention will be particularly pointed out in the appended claims.

My invention is illustrated in the accompanying drawings, forming part of this application, in which—

50 Fig. 1 is a front view of the device,
Fig. 2 is a side view of one of the braces,
Fig. 3 is an edge view of one of the braces,
Fig. 4 is a section along the line 4—4 of Figure 1.

55 Fig. 5 is a perspective view of a portion of the device.

In carrying out my invention, I provide a plurality of water tubes of the shape shown in the drawings. These tubes are of varying thicknesses at different portions, bent back and forth to form loops, as clearly 60 shown in the drawings. I have shown these tubes at A, B, and C respectively, it being understood that as many tubes as desired may be used, depending upon the size of the radiators. Each of the tubes is joined at the 65 top to a header E and also at the bottom to a header F. To this end each tube is provided with a flange G abutting the header, the body portion of the tube entering the header, as shown in the drawings.

70 Consider Fig. 4. In this figure, it will be seen that the thickness of each tube varies at different points. The largest thickness is shown at H and the smallest at K, the thickness H being twice that of K. The 75 opposed sections of the tube are joined together by lock seam joints M, thus insuring against leaking. These joints are designed to be soldered.

70 Cooperating with the tubes are braces, such as that shown at P. These braces have openings Q arranged to admit the curved portions of the loops or convolutions of the tubes. The braces are curved or corrugated in the manner shown and are soldered, or otherwise secured to the adjacent portions of the tubes. This renders the construction exceedingly strong and one which is not liable to be easily broken. The braces are also curved or fluted in a transverse direction, as will be 90 seen from Figure 4, to conform to the varying diameter of the water tubes. The braces, however, terminate short the ends of the tubes. The distance between adjacent tubes, i. e., the distance at R, is preferably one-half of the largest diameter of the tube. The distance between the convolutions or bends of the tube, i. e., from center to center, as shown at S, is twice the largest thickness 95 of the tube, while the distance from the center of one bend to the center of the adjacent one, i. e., the distance T, is four times the largest thickness of the tube. These dimensions are the preferable ones, but may vary without departing from the spirit of the invention.

100 The radiator constructed as described has a large radiating capacity compared with its dimensions. It is not liable to clog up, owing to the increased thickness of the tubes 110

at various points. The braces and tubes being flexible due to their shape, will withstand shocks and jars, which would tend to break or dismantle the ordinary radiator.

5 I claim:

1. An automobile radiator construction comprising an upper and a lower header, a plurality of water pipes extending from said upper to said lower header, said pipes being bent back and forth to form U-shaped loops, adjacent pipes having loops oppositely disposed, a brace disposed between the adjacent pipes, each of said braces having an opening to receive the bent portion of 15 the contiguous loops and being secured to said bent portions.

2. An automobile radiator construction comprising an upper and a lower header, a plurality of water pipes extending from 20 said upper to said lower header, each of said pipes being bent back upon itself to form a series of U-shaped pipes, each of said pipes having its sides bowed inwardly at a plurality of points from front to rear of 25 the pipe to provide varying diameters, and bracing devices extending from the upper to the lower header and having openings arranged to receive the bent portions of adjacent pipes, said bracing devices being 30 curved to conform with the varying diam-

eter of the pipes and being secured to the pipes at the U-shaped bends.

3. An automobile radiator construction comprising an upper and a lower header, a plurality of water pipes extending from 35 said upper to said lower header, each of said pipes being bent back upon itself to form a series of U-shaped pipes, each of said pipes having its sides bowed inwardly at a plurality of points from front to rear of the 40 pipe to provide varying diameters, bracing devices extending from the upper to the lower header and having openings arranged to receive the bent portions of adjacent pipes, said bracing devices being curved to 45 conform with the varying diameter of the pipes and being secured to the pipes at the U-shaped bends, and a pair of bracing devices between the adjacent pipes, each of said bracing devices having openings arranged to receive the bent ends of the loops 50 of adjacent pipes, said bracing devices being curved to contact with the adjacent bracing devices and being secured to the pipes at the bends in the latter, each of said bracing devices being curved to conform with the varying diameter of the device to which 55 they are secured.

ANTHONY V. KNOLL.
